UNITED STATES PATENT OFFICE.

CHRISTIAN CHRISTIANSEN, OF SIOUX FALLS, SOUTH DAKOTA.

GRAIN-SHOCKING MACHINE.

1,295,271.

Specification of Letters Patent.

Patented Feb. 25, 1919.

Application filed June 10, 1918. Serial No. 239,163.

To all whom it may concern:

Be it known that I, CHRISTIAN CHRISTIANSEN, a citizen of the United States, residing at Sioux Falls, in the county of Minnehaha and State of South Dakota, have invented certain new and useful Improvements in Grain-Shocking Machines; and I do declare the following to be a full, clear, and exact description of the invention, such as will 10 enable others skilled in the art to which it appertains to make and use the same.

My invention has for its principal object to provide a comparatively simple and inexpensive, yet an efficient and durable machine for receiving grain from a binder or like harvester, forming it into shocks, and depositing such shocks on the ground.

In carrying out the above, a further object is to provide novel means for laying 20 the grain flat and stacking the same in orderly fashion to form the shock, the arrangement being such as to dispose all heads toward the center of the shock, thus giving the latter the desired crown to shed water.

Still further objects are to provide effective means for shifting the grain receiver rearwardly to dumping position and to automatically open a rear gate thereof to permit discharge of the shock.

Yet another object is to provide for the automatic raising of the grain delivery chute when the receiver moves rearwardly.

With the foregoing objects in view, the invention resides in the novel features of 35 construction and unique combinations of parts to be hereinafter fully described and claimed, the descriptive matter being supplemented by the accompanying drawings which form a part of this application and in which:

Figure 1 is a side elevation of the machine with the several parts in position to receive the grain;

Fig. 2 is a longitudinal section with the several parts standing as seen in Fig. 1;

Fig. 3 is a side elevation of the machine with the parts disposed for dumping;

Fig. 4 is a longitudinal section of the machine in the condition depicted in Fig. 3;

Fig. 5 is a horizontal section taken substantially on the plane of the line 5—5 of Fig. 1;

Fig. 6 is a bottom plan view; and

Figs. 7 and 8 are vertical transverse sections on the planes indicated by the lines 7—7 and 8—8 respectively of Fig. 1.

In the drawings above briefly described, the numeral 1 designates a main horizontal frame mounted at its rear end on a pair of driving wheels 2 and at its front end on a 60 caster wheel or the like 3. A pair of suitably shaped side frames 4 rise from the sides of the frame 1 and a bearing carrying frame 5 is carried by and positioned below the latter. Frame 5 is provided with a central bearing 6 in which a journal 7 is rotatably received, said journal depending from a horizontal platform 8 upon which the grain is received, a sprocket chain or like device 9 being provided for rotating the platform 70 for a purpose to appear. As seen most clearly in Figs. 6 and 7, chain 9 is driven by a sprocket 10 which is in turn driven by a bevel gear 11, said gear meshing with a bevel pinion 12 slidable along a transverse 75 drive shaft 13 which is constantly rotated from one or both of the wheels 2, by means of suitable sprocket chains or the like 14. An arm 15 is provided for shifting the pinion 12 out of mesh with gear 11 to suspend 80 rotation of the platform when the completed shocks are being dumped, and by the provision of means yet to be described, this arm is operated simultaneously with the actuation of the means employed for discharging the shocks.

The pinion 12, gear 11, sprocket 10, and chain 9 are by preference employed for transmitting power from the shaft 13 to the platform 8, but it is to be understood that 90 any other preferred severable driving connections could well be used should occasion so demand. Furthermore, such connections may be located at any advantageous points.

A grain receiver R is mounted on the 95 frame of the machine and is normally positioned over the rotating platform 8, said receiver consisting of a front substantially semi-cylindrical section 16 and a rear gate section 17. Section 16 is provided on its 100 sides with shoes 18 traveling along longitudinal tracks 19 with which the side frames 4 are provided, said tracks being preferably of angle iron formation as shown. The gate section 17 is also of approximately semi-cylindrical shape and is provided on its upper end with a pair of upstanding arms 20 which are pivoted at 21 to parts of the side frames 4, the pivots being located considerably above the upper end of section 16. By 110 the means yet to be described, the section 16 of the receiver is shifted rearwardly from

the platform 8 to discharge the shock (see Figs. 3 and 4) and when this is done, it is necessary that the gate section 17 shall be swung upwardly and rearwardly to permit 5 free discharge of the shock. In order to obtain this result, the section 16 is provided with rollers or other suitable shoes 22 which about the front edge of the section 17 and raise the latter to an out of the way position 10 when said section 16 is shifted to dumping position. It is to be observed however, reference being still made to Figs. 3 and 4, that the gate section 17 does not swing upwardly to an entirely horizontal position. 15 This is highly desirable, since the weight of this section acting upon the shoes 22, serves to return the front section 16 forwardly after dumping of the load and release of the shifting means of said section. 20 The mechanism for shifting the receiver section 16 rearwardly, preferably consists of a pair of side chains 25 mounted on the side frames 4 and connected at 26 with the ends of a U-shaped bail 27 (see Figs. 1, 3, 4 and 5, 25 said bail being pivotally mounted at 28 on the front side of the section 16. Sprocket chains 29 are employed for driving the chains 25 from the shaft 13 when the clutches 30 are thrown into operation, there- 30 by moving said chains 25 to pull the receiver section rearwardly to the position shown in Figs. 3 and 4, thus causing the latter to raise the gate section 17 to discharge the load. Simultaneously with this operation, 35 the arm 15 is operated to arrest rotation of the table 8 as above set forth.

It may here be pointed out that although the chains 29 and clutches 30 are by preference used for driving the side chains 25, 40 any other suitable severable driving connections could well be employed between these parts. In all cases, however it is essential that adequate control means be employed to actuate the chains 25 and discharge the 45 shock immediately upon completion of the latter. These control means may of course be embodied in numerous forms and may be located wherever desired. For illustrative purposes however I have shown (Figs. 50 6 and 7) a pair of sliding rods 31 for operating the clutches 30, links 32 pivoted to the inner ends of said rods, a lever 33 to which said links are connected, and a pull rod 34 for so rocking said lever as to slide the rods 55 31 to throw the clutches 30 in and out as required. The arm 15 is carried by one of the rods 31 as shown clearly in Figs. 6 and 7 and it will thus be obvious that when these clutches are thrown into play to shift the receiver rearwardly, the pinion 12 is simultaneously shifted out of mesh with the gear 11, thus arresting rotation of the platform 8 until the load has been discharged. 60

Coacting with the platform 8 in correctly 65 positioning and packing the grain, while

said platform is rotating, are a pair of floating substantially conical rollers 35, said rollers being positioned in the receiver R and mounted on the crown bar 36 of an arched support 37, the ends of said support having 70 shoes 38, which are slidably freely along vertical tracks or other suitable guides 39 secured to the opposite sides of the front receiver section 16. The smaller ends of the rollers 35 are disposed inwardly and as the 75 grain is deposited in the receiver, the rotating platform and the rollers co-operate in laying such grain flat upon the former with the heads disposed inwardly. As the receiver is gradually filled with the grain, the 80 rollers 35 are raised by such grain and since the entire body of the latter is being rotated by the platform, said rollers not only retain the grain in orderly fashion, but effectively pack the same. By positioning all of the 85 heads of the grain at the center, the necessary crown is imparted to the shock to cause the same to shed water freely.

For the purpose of feeding the grain from the binder or the like into the receiver R, a chute 40 is provided, said chute being shown located transversely of the machine and pivoted at 41 on a horizontally swinging support 42, said support being in turn pivoted at 43 on a suitable bracket 44 secured to one of the frames 4. A control rod or the like 45 is connected to the support 42 so that it may be adjusted as occasion may demand to so locate the delivery end of the chute 40 as to obtain the best results. When the receiver is shifted rearwardly, it is necessary to raise the chute 40 to postpone feeding of the grain from said chute until the receiver has again returned to its initial position. To so raise the chute, an arched lever 46 has its front end fulcrumed at 47 to one of the side frames 4, while the rear end of said lever inclines downwardly and rearwardly as seen at 48, being preferably though not necessarily curved. A lateral shoe 49 on the front receiver section 16, underlies the lever end 48 and it will thus be seen (Fig. 3) that when said section 16 is shifted rearwardly, the lever 48 will be rocked, and since the chute 40 rests on the arched portion of the lever in question, it will be adequately raised. Forward return of the receiver section 16 will again permit lowering of lever 48 and consequently the chute 40 will return to operative position and again deliver 115 grain into the receiver. 120

The machine is intended principally to receive loose grain from any form of harvesting machine, and will operate effectively to lay such grain flat and form a shock thereof in the receiver R, with all of the heads disposed inwardly. The moment the shock is completed, the rod 34 is operated to throw the two clutches 30 into play and to simultaneously unmesh the pinion 12. The 130

result is that the rotation of the platform 8 ceases and the receiver is shifted rearwardly to dumping position; the gate section 17 then raising as shown in Figs. 3 and 4. This 5 dumping operation takes place so quickly as to avoid any possibility of the shock tilting and being thus disintegrated as it leaves the platform. When the rod 34 is released to throw the clutches 30 out of play, the 10 weight of the gate section 17 acts upon the shoe 22 and returns the front section 16 to its initial position, whereupon chute 40 is again lowered and continues to discharge grain 15 into the receiver. At the same time, pinion 12 is again meshed with gear 11, so that the platform 8 continues to rotate.

From the foregoing, taken in connection with the accompanying drawings, it will be obvious that although the machine is of 20 comparatively simple and inexpensive nature, it will be highly efficient and in every way desirable. Since probably the best results are obtained from the several details shown and described, they are by preference followed, but within the scope of the invention as claimed, considerable latitude is allowed for making such minor changes as occasion may dictate.

I claim:

50 1. In a grain shocking machine, a wheeled frame, a platform rotatable on said frame, a receiver above said platform formed of a front forwardly and rearwardly slidable section and a rear gate section, said rear section being automatically opened when said front section moves rearwardly, means for rotating said platform, grain packing means in said receiver, and means for shifting said front receiver section rearwardly from said 40 platform.

2. In a grain shocking machine, a wheeled frame, a receiver for said frame in which the shocks are formed, said receiver consisting of a forwardly and rearwardly slidable 45 front section and an upwardly and rearwardly swinging rear gate section, the latter being pivoted to said frame above said front section, whereby rearward sliding of said front section will raise said rear section, and 50 means for moving said front section rearwardly.

3. A grain shocking machine comprising a main wheeled frame, a platform thereon, a pair of side members rising from said 55 frame on opposite sides of said platform, a shock forming receiver over said platform and consisting of a front forwardly and rearwardly slidable section and a rear gate section, arms rising from said gate section 60 and pivoted at their upper ends to said side members, means for sliding said front section rearwardly, and shoes on said front section to abut and open said gate section as the former is moved rearwardly.

65 4. In a grain shocking machine, a wheeled

frame, a platform rotatable on said frame, a receiver above said platform formed of a front forwardly and rearwardly slidable section and a rear gate section, said rear section being automatically opened when said 70 front section moves rearwardly, means for rotating said platform, floating grain packing means in said receiver, and means for shifting said front receiver section rearwardly from said platform. 75

5. In a grain shocking machine, a wheeled frame, a platform rotatable on said frame, a receiver above said platform formed of a front forwardly and rearwardly slidable section and a rear gate section, said rear section being automatically opened when said front section moves rearwardly, means for rotating said platform, vertical guides at the sides of said front section, a support movable freely along said guides, and grain 80 packing means mounted on said support; together with means for shifting said front receiver section rearwardly from said platform. 85

6. In a grain shocking machine, a wheeled 80 frame, a platform rotatable on said frame, a receiver above said platform formed of a front forwardly and rearwardly slidable section and a rear gate section, said rear section being automatically opened when said 85 front section moves rearwardly, means for rotating said platform, vertical guides, at the sides of said front section, an arched support having shoes at its ends movable freely along said guides, and grain packing 100 rollers mounted on the crown bar of said support; together with means for moving said front receiver section rearwardly from said platform.

7. A grain shocking machine comprising 105 a main wheeled frame, a platform mounted on said frame, a pair of side frames rising from said main frame and having horizontal tracks extending longitudinally of the line of draft, a shock forming grain receiver between said side frames and positioned over said platform, said receiver consisting of a front and a rear section, said front section having shoes slidable along said tracks, and means for sliding said front section rearwardly from said platform, said rear section being automatically movable away from 110 said front section when the latter is moved rearwardly. 115

8. A grain shocking machine comprising 120 a wheeled frame, a shock forming receiver on said frame slidable rearwardly to dumping position, a pair of side chains mounted on said frame, means for operating said chains to move same rearwardly, and a bail 125 pivoted at its center to the front side of said receiver and connected at its ends to said chains.

9. A grain shocking machine comprising a 130 wheeled frame, a shock forming receiver

mounted thereon, means for sliding said receiver rearwardly to dumping position, a chute for delivering the grain into said receiver, a longitudinal lever on which said chute rests, and a shoe on said receiver slidably engaging said lever for raising the latter when said receiver is moved rearwardly.

10. A grain shocking machine comprising a wheeled frame, a shock forming receiver mounted thereon, means for sliding said receiver rearwardly to dumping position, a chute for delivering the grain into said receiver, a longitudinal lever on which said chute rests, said lever having a downwardly and rearwardly inclined rear end, and a shoe on said receiver underlying said inclined lever end to raise said lever when said receiver is moved rearwardly.

11. A grain shocking machine comprising

a wheeled frame, a platform mounted thereon, a driven shaft mounted on said frame, severable driving connections between said shaft and platform for rotating the latter, a receiver slideable on said frame above said platform and grain packing means in said receiver, means for shifting said receiver rearwardly to dumping position, severable driving connections between said shaft and said shifting means, and means for simultaneously throwing all of said severable driving connections out of play.

In testimony whereof I have hereunto set my hand.

CHRISTIAN CHRISTIANSEN.
